(No Model.)

P. DORGEVAL.

MACHINE FOR WASHING AND BEATING YARN.

No. 244,201.

Patented July 12, 1881.

UNITED STATES PATENT OFFICE.

POLYDOR DORGEVAL, OF PATERSON, NEW JERSEY.

MACHINE FOR WASHING AND BEATING YARN.

SPECIFICATION forming part of Letters Patent No. 244,201, dated July 12, 1881.

Application filed March 3, 1881. (No model.)

To all whom it may concern:

Be it known that I, POLYDOR DORGEVAL, of Paterson, in the county of Passaic and State of New Jersey, have invented a new 5 and useful Improvement in Machines for Washing and Beating Yarn, of which the following is a specification.

My improvements relate to machines for washing yarn in hanks, and have for their object to facilitate the introduction and removal 10 of the hanks and to render the washing operation perfect.

I make use of a rotary washer having rods on which the yarn is hung, and a spring beater-board for effecting the washing thoroughly.

The invention consists in certain novel features of construction and combination, as described and claimed hereinafter.

In the accompanying drawings, Figure 1 is 20 a vertical section of the machine transversely of the rotary washer, and Fig. 2 is a horizontal section of the machine.

Similar letters of reference indicate corresponding parts.

The box A is of suitable size and shape, and 25 is furnished at the front with doors, which permit convenient access to the interior of the box. At the inside of box A and on opposite sides are fixed blocks or plates a, that are 30 formed with circular recesses, that receive the heads of the rotary washer, so as to surround the same.

The rotary washer consists of circular heads b b, tied together by rods c and fitted with 35 removable hollow bars d, that carry the yarn. The heads b are formed with radial slots at their edges, and the bars d are fitted at their ends with collars d', that enter the slots c'. The plates a are formed at one side with slots or 40 grooves a' a'', extending from the central aperture to the edge, and inclined in opposite directions, to allow insertion and removal of bars d. The slots a'' are closed next to the heads b by blocks e, that are inserted from the outside 45 through apertures in the sides of box A, so that they can be removed at will. Pivoted latch-bars f, hung on box A and engaging with blocks d, serve to retain them in position as moved. Strips p are fitted in the slots a' a'', 50 and extend from heads b to the doors at the front of the box, for sustaining the bars d, as

hereinafter described. The heads b are formed with hollow gudgeons b'', that pass through bearings in the sides of the box, whereby the washer is sustained. Outside the box the 55 gudgeons are fitted with gear-wheels h, carried by a cross-shaft, to which power is to be applied for turning the washer. The gearing is applied in connection with both heads b, to prevent the washer from twisting, which might 60 occur if power were applied to one head alone.

A water-supply pipe, i, from a suitable source of supply enters the box A through the hollow gudgeons b''. Within the box the pipe is formed with numerous holes for outlet of the water. 65

The box A also contains the beater-board k, which is hung at one side of the rotary beater, on a level, or nearly so, with the under sides of heads b. It consists of a flat wooden board or strip having its inner edge rounded, and 70 having pivots k', that extend through apertures in the sides of box A. On the outer ends of pivots k' there are arms l l, to which springs m m are connected. The springs tend to raise the inner edge of the board, such 75 movement being limited by pins n above the arms l, inserted in holes provided in the box-sides. The board is thus held in a horizontal position, or more or less inclined, as desired.

In operation the yarn in hanks is placed on 80 bars d while removed from the box. The bars are then placed in the upper slots, a', upon the strips, one after another, the upper blocks, e, are pulled out, and the washer being then revolved, the bars drop into the slots c' as such 85 slots come in succession to the slot c'. Blocks e are then pushed inward, and the bars d are thus retained in place. The water from pipe i saturates the yarn as it hangs, and passes out freely by an outlet at the bottom of the box, 90 so that there is no accumulation of water. As the heads b revolve the enlarged ends of rods d fall successively in contact with the blocks a when at their lower position, and the rods d being thus turned, the hanks of yarn are turned 95 so that every portion is subject to the washing and beating. The hanks are thrown on the board k as the washer revolves, and are thus given the beating required for their thorough washing. The springs allow the beater-board 100 to give way to the strokes, so that the beating action is softened more or less, according to the

tension of the springs. When the washing is completed the blocks *e* in slot *a*² are to be drawn out, and the bars *d*, as they come in succession to the end of slot *a*², will roll out 5 and down upon the strips *p*, from whence they can be removed conveniently. The operations are thus rapidly and readily carried out.

Having thus described my invention, I claim as new and desire to secure by Letters Patent—

10 1. In machines for washing and beating yarn, the rotary washer, consisting of heads *b*, tied by rods *c*, sustained by hollow gudgeons *b*², and fitted with the removable bars *d* for carrying the yarn, substantially as shown and 15 described.

2. In machines for washing and beating yarn, the beater-board *k*, hung on pivots at its ends and sustained by springs, combined with the rotary washer carrying the yarn, substantially as shown and described. 20

3. In machines for washing and beating yarn, the recessed end plates or boards, *a*, formed with the slots or grooves *a*' *a*², and the adjustable blocks *e*, combined with the rotary washer having slotted heads *b*, and the bars *d*, 25 carrying the yarn, substantially as and for the purposes set forth.

4. The combination, in yarn washing and beating machines, of a rotary washer carrying the yarn, a spring beater-board, perforated 30 water-pipe passing through the axis of the washer, and an inclosing-box, substantially as shown and described.

POLYDORE DORGEVAL.
